UNITED STATES PATENT OFFICE.

GEORGE H. ISLEY, OF WORCESTER, MASSACHUSETTS, ASSIGNED TO MORGAN CONSTRUCTION COMPANY, OF WORCESTER, MASSACHUSETTS, A CORPORATION OF MASSACHUSETTS.

GAS-PRODUCER.

1,221,055.

Specification of Letters Patent.

Patented Apr. 3, 1917.

Application filed June 30, 1913. Serial No. 776,523.

To all whom it may concern:

Be it known that I, GEORGE H. ISLEY, a citizen of the United States, residing at Worcester, in the county of Worcester and Commonwealth of Massachusetts, have invented a new and useful Improvement in Gas-Producers, of which the following, together with the accompanying drawing, is a specification.

10 My invention relates to gas producers and more particularly to the hopper or mechanism for supplying fuel to the producer.

One object of my invention is to provide an improved form of fuel feeding mechanism so arranged and constructed that it will spread the fuel evenly and uniformly over the fuel bed.

Another object is to provide adjusting means to correct the operation of the feeding mechanism if it is found, at any time, that the fuel is not being spread evenly.

Another object is to provide adjusting means to regulate the rate of supply of the fuel in accordance with the rate of consumption thereof in the producer.

Further objects and advantages will appear from the following description taken in connection with the accompanying drawing, in which Figure 1 is a vertical sectional view of the upper portion of one form of gas producer constructed in accordance with my invention; Fig. 2 is a vertical sectional view of the upper portion of a producer embodying a modified form of the invention; Fig. 3 is a view of a portion of Fig. 1, but with the lower section of the hopper in a different position of adjustment; and Fig. 4 is a plan view of the hopper.

Similar reference characters refer to similar parts in the different figures.

In the form of the invention shown in Fig. 1, the gas producer includes a stationary upper section 1 and a rotatable fuel section 2, there being a water sealed joint 3 between the sections. The rotatable section 2 may be rotatably supported in any suitable manner so that it may be rotated by the worm gear 4 which engages the circular rack 5 encircling the rotatable section. It is preferred that the fuel section 2 of the producer be rotatable and that the section 1 of the producer carrying the fuel feeding mechanism be stationary, as shown. It will

be obvious as the description proceeds, however, that the same results would be obtained by rotating either of the sections relatively to the other. The top 6 of the upper stationary section 1 is provided with an opening 7 for my improved feeding mechanism, this opening being offset toward one side of the producer.

The feeding mechanism includes a hopper composed of an upper section 8 and a lower section 9. The lower end of the section 8 is contracted in the usual manner and preferably extends slightly into the upper end of the section 9 so that none of the fuel descending through the hopper can pass through the joint between the two sections. The section 8 of the hopper is provided with a flange 10 by means of which it is mounted fixedly upon the top 6 of the producer and in register with the opening 7. The section 9 of the hopper is suspended by three bolts 11 spaced equally about the hopper. These bolts are attached at their lower ends to ears or wings 12 integral with and projecting from the periphery of the section 9 of the hopper. The upper ends of the bolts 11 are threaded and each carries a pair of nuts 13 and 14. The nuts 13 are adapted to seat against the supporting frame so as to bear the weight of the bolts 11 and the mechanism supported thereby. The nuts 14 are more or less elongated so that they may extend beyond the ends of the bolts to contact with the seats 15, the seats 15 being in alignment with the bolts so as to hold the bolts and the section 9 of the hopper rigidly in place. The opposing forces of the two nuts 14 on each bolt serve further to lock the nuts in place so as to prevent accidental change in adjustment thereof.

The space below the discharge opening 16 of the section 9, which opening is also, of course, the discharge opening of the hopper as a whole, has a supporting shelf or table 17 to receive the fuel as it is discharged from the hopper. This table 17 is offset toward one side of the producer in a position approximately concentric with the vertical axis of the hopper as a whole, but with the outer edge of said shelf more nearly beneath the discharge opening 16 than the inner edge and it is supported by three hollow supports 18 depending from some suitable fixed por-

tions of the frame of the producer. In order to prevent injury to the shelf 17 by the heat generated in the producer, the shelf is provided with a hollow space 19 to accommodate a cooling current of water, a supply pipe 20 conducting the water to the hollow shelf and a discharge pipe 21 conducting the water from the shelf after it has become heated. The pipes 20 and 21 are preferably located in the hollow supports 18 in order to give the pipes as much protection as possible from the surrounding heat.

The scraper 22, composed of horizontal rotatable arms, is located in the space between the shelf and the bottom of the hopper and preferably close to, or in contact with, the top of the shelf. The scraping arms are carried upon a vertical shaft 23 pivoted near its lower end in a bearing at the center of the shelf and at its upper end in a bearing in the upper portion of the hopper. The shaft 23 and the scraper 22 are driven by a driving shaft 24, the two shafts being connected by a pair of bevel gears 25 and 26. The driving shaft 24 is actuated by a pawl 27 and ratchet 28.

The upper rim 29 of the hopper is pivoted at its center and has a floor 30 provided with openings 31. The pivoted handle 32, when raised into a horizontal position, serves to rotate the rim 29 and its floor about its vertical axis to bring the openings 31 into register with coöperating openings in the top 33 of the section 9 of the hopper so that fuel which has been placed inside the rim 29 may drop through the openings and thence downwardly onto the shelf and into the path of the scraper 22.

One important feature of the invention resides in the fact that the discharge opening 16 of the hopper is offset toward the outer edge of the shelf 17 or, in other words, that it is eccentric with relation to the shelf. The arms of the scraper 22 rotate about a vertical axis at the center of the shelf and it is obvious that, if the discharge opening of the hopper were concentric with the axis of the scraper so as to deposit the fuel centrally upon the shelf, the fuel would be caused to pass uniformly over all portions of the edge of the shelf. As the section 9 of the producer rotates, however, the center of the surface of the mass of fuel 34 moves much more slowly than do the outer portions of its surface, with the obvious result that a considerably greater quantity of fuel would be deposited upon the central portion of the surface of the fuel than upon its outer portions. By arranging the lower end of the hopper and its discharge opening 16 eccentrically with relation to the shelf 17 and toward the outer edge thereof, the fuel is deposited upon the shelf nearer to the outer than to the inner edge so that the scraper will cause greater quantities of fuel

to pass over the outer edge of the shelf than over the inner edge. The eccentricity of the lower end of the hopper and its discharge opening with relation to the shelf is such that the fuel will be deposited uniformly upon the different portions of the surface of the mass of fuel 34 or, in other words, the rate of supply of fuel is greater from those portions of the edge of the shelf overlying the more rapidly moving parts of the mass of fuel 34 than from those portions of the edge of the shelf overlying the less rapidly moving parts of the mass of fuel.

It is sometimes necessary, or desirable, to increase or decrease the rate at which the fuel is being supplied to the producer by the feeding mechanism. For instance, if the blast is increased or decreased in order to increase or decrease the output of the producer, the demand for fuel will be varied accordingly. The character of the fuel being supplied to the producer may vary so that without adjustment of the feeding mechanism the rate at which the fuel is supplied will be caused to vary. The lower section 9 with the discharge opening 16 of the hopper is, therefore, arranged to be vertically adjustable to and from the shelf 17 for the purpose of varying the rate at which the fuel will be supplied to the producer. It is clear that as the section 9 of the hopper is moved upwardly away from the shelf 17 so as to increase the space between them in which the scraper 22 rotates, the fuel will naturally spread out into a wider circle upon the shelf or, in other words, a greater quantity of fuel will lie in the path of the arms of the scraper at any instant of time so that the rate at which fuel is caused to pass over the edges of the shelf by the scraper is increased. Conversely, as the section 9 with the discharge opening of the hopper is moved downwardly toward the shelf so as to decrease the space between them within which the scraper rotates, the rate at which the fuel is caused to pass over the edges of the shelf will be decreased.

This vertical adjustment of the section 9 of the hopper is effected by adjusting the positions of the nuts 13 and 14 on the bolts 11 so as to raise or lower the bolts together with the section 9 of the hopper as desired. It is clear that by adjusting the position of one or two only of the bolts so as to raise or lower one side of the section 9 of the hopper above or below its other side, as shown in Fig. 3, the space intervening between the shelf and the section 9 of the hopper will be greater at one side than at the other so that the fuel will be caused to pass more rapidly over that portion of the edge of the shelf lying under the highest part of the section 9 of the hopper than at that portion of the edge of the shelf lying under the lowest part of the section 9.

In the modified form of the invention shown in Fig. 2 of the drawing, the general construction is similar to that indicated in Fig. 1 and the same reference characters are used to indicate similar parts except that in Fig. 2 the reference characters are primed. In Fig. 2 the hopper is shown as constructed with an intermediate section 35' supported from fixed portions of the frame by bolts 11' so as to be vertically adjustable in the same manner and for the same purpose as described in connection with the structure shown in Fig. 1. The lower section 9' of the hopper is suspended from the intermediate section 35' by three links 38', pivotally connected at their upper ends to the intermediate section 35' and at their lower ends to the lower section 9' of the hopper. This three point suspension by means of pivotally connected links allows the lower section 9' together with the discharge opening 16' of the hopper to move freely in any direction in a substantially horizontal plane. Three bolts 37' with their nuts 38', spaced equally about the section 9' of the hopper and connected thereto at their inner ends and to the fixed frame at their outer ends constitute means for adjusting the horizontal position of the lower section and the discharge opening of the hopper and for holding them in any desired adjusted position. Ordinarily the desired degree of offset of the discharge opening of the hopper toward the outer edge of the shelf may be predetermined so that no adjustment is necessary in order to secure fairly even distribution of the fuel. By arranging the lower section of the hopper so as to be adjustable horizontally, however, a still more accurate distribution may be obtained and this is often very desirable.

While I have shown and described the details of certain forms of my invention, I do not wish to be limited to such details as it is obvious that changes may be made within the scope of the appended claims without departing from the spirit of the invention; but having described my invention, what I claim as new and desire to secure by Letters Patent is:

1. In a gas producer, a fuel section, a fuel feeding mechanism disposed eccentrically to said fuel section, comprising a hopper, and a shelf below said hopper offset toward the center of said fuel section and eccentric to said fuel section and to said hopper, and means for causing relative rotation between said fuel section and said fuel feeding mechanism.
2. A gas producer including a casing having a section for the fuel, a shelf horizontally eccentric to the casing, and a hopper above the shelf, the discharge opening of the hopper being horizontally eccentric to the shelf and the fuel section, means for causing relative rotation between said fuel sec-

tion and said hopper and shelf, and means for crowding the fuel over the edges of said shelf.

3. A gas producer including a casing having a section for the fuel, a shelf horizontally eccentric to the casing, a hopper above the shelf, the discharge opening of the hopper being horizontally eccentric to the shelf and the fuel section, means for causing relative rotation between said fuel section and said hopper and shelf, and rotating means, concentric with the discharge opening of the hopper, for crowding fuel over the edges of said shelf.

4. In a gas producer, a shelf, a hopper above the shelf, the discharge opening of the hopper being offset toward one side of the shelf, and rotating means concentric with said shelf for causing fuel resting on the shelf to pass over the edge thereof.

5. In a gas producer, a shelf, and a hopper above the shelf, and means for adjusting the lower end of the hopper relatively to the shelf.

6. In a gas producer, a shelf, and a hopper above the shelf, and an adjusting means for varying the relation between the lower end of the hopper and the shelf.

7. In a gas producer, a shelf, a hopper above the shelf, and means for causing relative horizontal adjustment of the lower end of the hopper and the shelf.

8. In a gas producer, a shelf, and a hopper with its discharge opening above the shelf, and independent means for adjusting opposite sides of the discharge opening of the hopper to and from the shelf.

9. In a gas producer, a shelf, and a hopper with its discharge opening above the shelf, one side of the discharge opening being nearer the shelf than is the other side thereof.

10. In a gas producer, a shelf, and a hopper above the shelf and means for adjusting the lower end of the hopper in any direction.

11. In a gas producer, a shelf, a hopper above the shelf, means for adjusting the lower end of the hopper horizontally, and means for adjusting the lower end of the hopper vertically.

12. In a gas producer, a shelf, and a hopper above the shelf, and means for adjusting the lower end of the hopper relatively to the shelf in any direction.

13. In a gas producer, a shelf, a hopper above the shelf, the hopper having a lower section suspended to move freely in a substantially horizontal direction, and means to hold said section in desired position.

14. In a gas producer, a shelf, a hopper above the shelf, the hopper including two sections, means for adjusting one section of the hopper vertically to and from the shelf, and means for adjusting the other section of

the hopper horizontally relatively to the shelf.

15. In a gas producer, a shelf, and a hopper above the shelf, the hopper being mounted to one side of the vertical axis of the fuel bed, means for causing relative horizontal rotation between the fuel bed and the shelf and hopper, and means for discharging fuel

over different portions of the edge of the shelf at different rates.

Dated this 26th day of June, 1913.

GEORGE H. ISLEY.
